US00D833186S

(12) **United States Design Patent** (10) **Patent No.:** **US D833,186 S**
(45) **Date of Patent:** **** Nov. 13, 2018**

(54) **WORKBENCH**

(71) Applicant: **Yangzhou Higher Machinery Co., Ltd.**, Jiangsu (CN)

(72) Inventor: **Guilyun Xing**, Jiangsu (CN)

(73) Assignee: **YANGZHOU HIGHER MACHINERY CO., LTD.**, Jiangsu (CN)

(**) Term: **15 Years**

(21) Appl. No.: **29/591,817**

(22) Filed: **Jan. 24, 2017**

(30) **Foreign Application Priority Data**

Oct. 21, 2016 (CN) 2016 3 0516314

(51) **LOC (11) Cl.** **06-03**

(52) **U.S. Cl.**

USPC **D6/684**

(58) **Field of Classification Search**

USPC D6/641, 648.1, 672, 684, 713; D25/67

CPC B25H 1/02; B25H 1/04; B25H 1/14

See application file for complete search history.

(57) **CLAIM**

The ornamental design for a workbench, substantially as shown and described.

DESCRIPTION

FIG. 1 is a top view of a workbench comprising a new, original and ornamental design;

FIG. 2 is a front view thereof;

FIG. 3 is a rear view thereof;

FIG. 4 is a bottom view thereof;

FIG. 5 is a left side view thereof;

FIG. 6 is a right side view thereof;

FIG. 7 is a top, front and left side perspective view thereof;

FIG. 8 is a front view of the workbench shown with environment for ease of disclosure;

FIG. 9 is a top, front and left perspective view thereof;

FIG. 10 is a top, front and left side perspective view of the working surface shown separately from the workbench for ease of disclosure;

FIG. 11 is a top view thereof;

FIG. 12 is a front view thereof;

FIG. 13 is a rear view thereof;

FIG. 14 is a bottom view thereof;

FIG. 15 is a left view thereof; and,

FIG. 16 is a right view thereof.

A portion of the workbench is shown broken away to indicate that it has no particular length beyond what is shown.

The broken lines depict portions of the article that form no part of the claimed design.

1 Claim, 16 Drawing Sheets
